No. 608,060.

Patented July 26, 1898.

E. J. MALLEN.

PIPE COLLAR.

(Application filed Jan. 24, 1898.)

(No Model.)

UNITED STATES PATENT OFFICE.

EDWARD J. MALLEN, OF NEW YORK, N. Y.

PIPE-COLLAR.

SPECIFICATION forming part of Letters Patent No. 608,060, dated July 26, 1898.

Application filed January 24, 1898. Serial No. 667,799. (No model.)

To all whom it may concern:

Be it known that I, EDWARD J. MALLEN, of the city of New York, borough of Manhattan, in the county of New York and State 5 of New York, have invented a new and useful Improvement in Pipe-Collars, of which the following is a full, clear, and exact description.

My invention relates to pipe-collars especially adapted for exposed pipe-risers that pass through finished ceilings, floors, and walls.

The object of the invention is to construct such a device in a simple, durable, and economic manner and so that the device may be expeditiously and conveniently applied to hot-water or steam supply, steam or hot-water return, and air-vent pipes in pipe-risers without marring the ceiling or wall.

20 A further object of the invention is to so construct the device that it will admit of expansion and contraction and obviate cutting the templets, as the portions of the collar can be adjusted to suit any riser whether out of 25 line or square.

20 A further object of the invention is to provide a pipe-collar which will admit of the filling of fireproof material around the pipes and which will prevent the dropping of any 30 dirt and the passing of any noise or any bad odors from one floor to another.

The invention consists in the novel construction and combination of the several parts, as will be hereinafter fully set forth, 35 and pointed out in the claims.

Reference is to be had to the accompanying drawings, forming a part of this specification, in which similar characters of reference indicate corresponding parts in all the figures.

40 Figure 1 is a vertical section on the line 1 1 in Fig. 2 through a portion of the floor and ceiling, illustrating the application of the device. Fig. 2 is a bottom plan view of the device constructed for application to a ceiling, the pipes passing through the device being shown in horizontal section. Fig. 3 is a horizontal section taken substantially on the line 3 3 of Fig. 1, and Fig. 4 is a transverse section taken substantially on the line 4 4 of 45 Fig. 3.

50 A represents a section of flooring, B a por-

tion of the ceiling, and C the casing, which extends through corresponding openings made in the floor and in the ceiling, through which casing the steam-supply pipe D is passed, the 55 return-steam pipe D', and the air-vent D''. The body of the device may be given any desired shape. Preferably, however, it is of somewhat elliptical form and is in the nature of a plate 10, made in two sections a and a', 60 each section of the body being provided with a marginal flange 11 and with an inner opening 12. One section of the body is further provided with lugs 13 at its ends, the said lugs being formed at the inner face of the 65 section, and the lugs are arranged to extend over the corresponding surface of the opposing section of the body, the two sections of the body being connected by screws 14, which pass through the outer face of the section 70 overlapped by the lugs 13 and into said lugs only when the device is to be applied to a ceiling; but when the device is to be applied to a floor the screws 14 pass through and beyond the lugs and are made of sufficient 75 length to enter the floor, as shown at the upper portion of Fig. 1.

Upon what may be termed the "inner" face of the body lugs 15 are formed at the end at each side of the center, the lugs extending 80 inwardly or in direction of the center, and at each side of each section, also upon the inner face, a lug 16 is formed, extending from the flange inwardly or in direction of the center of the body.

85 In connection with the body usually three clamping-plates 17, 18, and 19 are employed, the clamping-plates 17 and 18 being at the end portions of the body and the clamping-plate 19 at the center. The clamping-plates 90 are held between the lugs 15 and 16 and the inner face of the body. The clamping-plate 17 is provided with an opening 17^a, adapted to receive, for example, the steam-supply pipe D, and spurs 17^b are formed at intervals 95 at the margin of the said opening to engage with the said pipe and allow of the expansion and contraction thereof. The clamping-plate 18 is similarly provided with an opening 18^a, receiving, for example, the return-steam pipe 100 D', and at the margin of this opening 18^a spurs 18^b are also formed to engage with the

pipe; but in the central clamping-plate 19 an uninterrupted opening 19^a is formed, which is adapted to receive an air-vent D².

The clamping-plate is provided with a cut 5 20 or is divided from one side to the opening 17^a. The clamp 18 is similarly provided with a cut or a division 21, and the central plate 19 also has a cut or a division 22 produced therein, extending from one of its edges 10 to the opening 19^a, as is clearly shown in Figs. 2 and 3. The clamping-plates are made of a spring material—as, for example, sheet-brass—and by reason of the cuts made therein the sections of the plates adjacent to the cuts 15 may be carried in opposite directions and the several plates readily slipped upon the pipes they are designed to receive. After the pipes have entered the openings in the plates and the plates are released they will 20 assume their normal position and be perfectly flat.

The end plates 17 and 18 slide over or rest upon the central plate 19 when the device is attached to a ceiling; but when the device is 25 attached to the floor the central plate will rest upon the end clamping-plates, as shown in Fig. 1. To this end recesses 23 are made in the central portion of each section of the body, as shown in Fig. 4, into which recesses 30 the central plate 19 is introduced. Under this arrangement the upper faces of the several lugs 15 and 16 may be in the same horizontal plane.

When the device is to be used upon a ceiling, in order that the ceiling shall not be unduly marred or broken the screws 14 are not carried into the ceiling, as heretofore stated. Instead of screws clamps E are employed, these clamps consisting of two upright members 35 40 24, each having a base member 25, the base members of the clamps being secured by screws 26 or other fastening devices to the central lugs 16. The upper portions of the members of the clamps diverge, and at the 45 upper extremity of each member or section of a clamp a toothed jaw 27 is formed, the jaws facing in direction of each other.

In the application of the device to a ceiling a suitable opening is made at opposite sides 50 55 of the casing C to admit the clamps, and the body portions of the clamps are forced upward, receiving between their sections or members the casing C, the jaws 27 of the clamps firmly engaging with the casing by reason of the clamp being made of spring-steel or a similar material, as is fully illus-

trated in Fig. 4. The clamps will have sufficient hold upon the casing to maintain the device in the position required. In order that the clamping-plates shall not have sufficient play to cause such displacement as to produce an opening in the device, projections 60 65 28 are formed upon the several clamping-plates, which by engagement with the walls of the opening 12 in the body-plate will limit the side movement of the clamping-plates.

Having thus described my invention, I claim as new and desire to secure by Letters Patent—

1. In a pipe-collar, a skeleton body-plate, 70 clamping-plates having pipe-receiving openings, each clamping-plate being provided with a cut extending from an edge to the pipe-receiving opening therein, and means, substantially as described, for holding the clamping-75 plates in the body-plate, as and for the purpose specified.

2. In a pipe-collar, the combination, with a body-plate, of clamping-plates adjustably held in the body-plate, the said body-plate 80 being provided with pipe-receiving openings, and cuts extending from the said openings to the outer edge of the several plates, as and for the purpose specified.

3. The combination, with a body-plate constructed in detachable sections, the said sections being provided with lugs, of clamping-plates held to slide in the body-plate between the said plate and its lugs, the clamping-plates being of a spring material and provided 90 with pipe-receiving openings, and cuts leading from the pipe-receiving openings of the plates to the outer edge thereof, for the purpose specified.

4. A pipe-collar consisting of a body-plate 95 constructed in removable sections, and clamping-plates adjustably and removably held in the body-plate, the clamping-plates being of a spring material, end clamping-plates being mounted to slide in engagement with a central clamping-plate, each clamping-plate having a pipe-receiving opening, and each clamping-plate being likewise divided at a portion in its surface, the division extending from the pipe-receiving openings to the outer edges 100 of the said plates, as and for the purpose specified.

EDWARD J. MALLEN.
